CLAIM

The ornamental design for sawhorse leg, as shown and described.

DESCRIPTION

FIG. 1 is a perspective view of a sawhorse leg showing my new design;

FIG. 2 is a side elevational view thereof;

FIG. 3 is an enlarged perspective view showing the clip; and,

FIG. 4 is an exploded perspective view thereof.

The broken lines showing a crossmember and additional legs are for illustrative purposes only and form no part of the claimed design.
